UNITED STATES PATENT OFFICE.

THOMAS E. CHANDLER AND ELIHU DODDS, OF INDIANAPOLIS, INDIANA,
ASSIGNORS TO THE CHANDLER & TAYLOR COMPANY, OF SAME PLACE.

DESIGN FOR AN ENGINE-BED.

SPECIFICATION forming part of Design No. 28,288, dated February 15, 1898.

Application filed February 8, 1897. Serial No. 622,547. Term of patent 14 years.

To all whom it may concern:

Be it known that we, THOMAS E. CHANDLER and ELIHU DODDS, citizens of the United States, residing at Indianapolis, in the county of Marion and State of Indiana, have invented and produced a new and original Design for Engine-Beds, of which the following is a specification.

The accompanying drawings illustrate our design for engine-beds.

Figure 1 is a perspective view of an engine-bed embodying our design, the view being taken from the top thereof. Fig. 2 is a perspective view taken from the cylinder end of the bed, and Fig. 3 is a perspective view taken from the shaft end of the bed.

The principal features of our design are the L-shaped plate 4, upon the base of the L of which are mounted the two standards 5 and 6 and the strengthening-rib 7. Plate 4

extends between and connects the bases of the standards 5 and 6. Rib 7 rises from the plate 4 near the upper part of the base of the L and connects the two standards 5 and 6, so as to form a space 8 between the adjacent sides of the said standards, the rear side of the rib, and the plate 4.

We claim as our invention and production—

The design for an engine-bed comprising the base-plate, the standards 5 and 6 erected thereon, to one side of the medial line of the cylinder, and a rib 7 connecting the standards and forming a space therebetween, substantially as shown and described.

THOMAS E. CHANDLER.
ELIHU DODDS.
